DESIGN FOR A COMBINED SACHET AND CONTAINER

Albert H. Newman, Chicago, Ill.

Application April 29, 1942, Serial No. 106,747

Term of patent 3½ years

To all whom it may concern:

Be it known that I, Albert H. Newman, a citizen of the United States, residing at Chicago, in the county of Cook and State of Illinois, have invented a new, original, and ornamental Design for a Combined Sachet and Container, of which the following is a specification, reference being had to the accompanying drawing, forming part thereof.

The figure is a front perspective view of a combined sachet and container showing my new design.

I claim:

The ornamental design for a combined sachet and container, as shown.

ALBERT H. NEWMAN.
